UNITED STATES PATENT OFFICE.

JOHN W. NASMITH, OF MANCHESTER, ENGLAND.

COMBING MACHINE.

Application filed January 16, 1922. Serial No. 529,528.

To all whom it may concern:

Be it known that I, JOHN WILLIAM NASMITH, a subject of the King of Great Britain, residing at Leegate, Heaton-Mersey, 5 Manchester, in the county of Lancaster, England, have invented certain new and useful Improvements in Combing Machines, of which the following is a specification, reference being had to the accompanying 10 drawings.

In my United States Patent No. 724,119 granted to me there is described on page 3, lines 104 to 109 et seq., the manner in which the top leather covered detaching roller is 15 caused to roll to and fro on the top of the bottom steel detaching roller and as hitherto arranged there has been a steady weight or pressure on the leather roller constantly throughout the stroke. But during the 20 greater part of the stroke no detaching is taking place and a small pressure, sufficient to ensure rotation of the top roller with the bottom one, would be enough until the rollers have seized the fibres composing the 25 nipper tuft and commence to draw them through the needles of the top comb. They offer considerable resistance which gradually increases until the top roller has reached the forward end of its stroke and the top 30 comb is close to the steel detaching roller. During this, the detaching period, a strong pressure is required on the roller to overcome this resistance.

The object of the present invention is 35 therefore to provide means whereby the pressure on the top roller shall vary automatically during each stroke so as to be reduced almost to nil when the roller has rolled back towards the combing cylinder and then 40 gradually increase to a maximum as the top roller approaches the forward end of its stroke. This being the case it becomes possible to put a much greater maximum pressure on the top roller during the brief instant towards the forward end of the stroke, than would be possible if that pressure had 45 to remain on during the whole stroke, and this is possible without risk of shortening the life of the leather covering of the top 50 roller. A further object is to combine with the arrangement means of easily removing the pressure from the top roller so that it can be freely and easily removed when necessary.

55 Figs. 1 and 2 are partial sections through the middle of one head of a Nasmith comb-

ing machine. Fig. 1 shows the top leather covered detaching roller in its most forward position just as the detaching process is ended and Fig. 2 shows it at the opposite extreme of its rolling movement when no detaching is taking place. Only one weight hook and relieving lever are shown, but it will be understood that there is an identical pair at each end of the roller in each head of the machine. Figs. 3 and 4 show alternative modifications of detail.

Referring to the drawings, F represents part of the framing of the machine, in which are journalled the cylinder shaft C and the 70 rocking shaft R and which carries the fixed pin P. It also carries bearings for the rollers D, D' and the shaft S. The two-armed operating lever L is keyed on the shaft S and rocked to and fro from the shaft R 75 through the adjusting link N, the shaft R being controlled in the usual manner by cam or eccentric in the head stock of the machine. The upper arm of the lever L carries a pin 1 upon which is loosely pivoted the hook-shaped member H, whose other end bears on the bush on the end of the top roller d. Attached to the lower part of the hook H is a tail T having a spring 2 connected to its lower end. The other end of the spring 2 is attached to a projection 3 formed on the long lever K which carries a pin 4 engaging in a notch formed in the swinging lever 5 pivoted freely on the pin P. The upper end of the long lever K is 90 conveniently, but not necessarily, pivoted loosely on the pin 1 alongside the hook H. The said lever K constitutes a swinging weight lever when the pin 4 is disengaged from the upper notch of lever 5, as herein-after described. In order to remove easily the roller d when required, a handle 6 is provided on the lever K so that it can be raised against the pull of the spring 2 until the pin 4 is clear of the top notch of the 100 lever 5, which is then pushed back and pin 4 allowed to fall into the lower notch of the lever 5. As the lever K falls a projection 7 cast on it comes against a face 8 formed on the weight hook H and as soon as this contact takes place the spring 2 is "dead" and the hook H and the lever K become as one piece so that the weight of the lever K holds up the hook H free of the neck of the roller d whilst the pin 4 rests in the lower notch 110 in the lever 5.

When the pin 4 is disengaged as explained,

the weight of the lever K, and the weight of the hook-shaped member H causes both the members K and H to swing, to raise the tip of the member H from the neck of the roller d as just described.

During each stroke of the machine the lever L moves uninterruptedly from the position shown in Fig. 1 to that shown in Fig. 2 and back again and carries with it the long lever K swinging on the lever 5 and pin P. In doing so the projection 3 moves nearer to the tail T and the tension of the spring is relaxed as the roller d rolls over towards the position shown in Fig. 2. But owing to the relative displacement at the same time of the center of 1 and that of the roller d the tail T also moves towards the projection 3 thus further relaxing the tension of the spring 2. As the opposite movement takes place the distance between 3 and T is gradually increased, gradually augmenting the tension of the spring as required to put the maximum pressure on the roller d at the forward end of its rolling movement.

By pivoting the lever K on the pin 1 a suitable displacement of the projection 3 is obtained but this displacement may be reduced by pivoting the lever K on an independent pin, 9 Fig. 3 fixed in the lever L but nearer the center of the shaft S and more in front of it so that the movement of the pin 9 is rather vertical than horizontal. Or the movement of 3 may be eliminated altogether by pivoting the lever K on the shaft S itself as in Fig. 4, when the relaxation of the pull of the spring will depend solely on the displacement of the lower end of the tail T. But it is preferable to have both the points to which the ends of the spring 2 are attached moving alternately towards and away from each other so that a lighter and more flexible spring may be employed than would be the case if only the point on the hook H were moving and the other end of the spring attached to some fixed point.

I claim:

1. In a combing-machine of the class wherein a top-detaching roller is moved to and fro on a lower roller relatively to the combing cylinder, the combination with said top-detaching roller of a spring and lever connections between the said top roller and spring to alternately relax and extend the spring as the said top roller moves toward and from the combing cylinder.

2. A combing-machine wherein a top-detaching roller is mounted to be moved to and fro on a lower roller relatively to the comb-

ing cylinder, said machine having a spring and lever connections between the said top roller and spring, characterized by the fact that the lever connections are constructed and arranged to cause the spring to be alternately relaxed and extended as the said top roller moves toward and from the combining cylinder.

3. In a combing-machine of the class wherein a top-detaching roller is moved to and fro on a lower roller relatively to the combing cylinder, the combination with said top roller of an operating lever, a weighted hook-shaped member connecting said operating lever and top roller, and a tension spring connected to said hook-shaped member, at a point of the latter which moves in the opposite direction to the top roller.

4. In a combing-machine of the class wherein a top-detaching roller is moved to and fro on a lower roller relatively to the combing cylinder, the combination with said top roller of an operating lever, a hook-shaped member connecting said operating lever and top roller, a swinging weight lever pivoted to the operating lever, and a tension spring connecting said weight lever and hook-shaped member.

5. In a combing-machine of the class wherein a top-detaching roller is moved to and fro on a lower roller relatively to the combing cylinder, the combination with said top roller, of an operating lever, a hook-shaped member connecting said operating lever and top roller, a swinging lever pivoted to the operating lever, and a tension spring connecting the said swinging lever and hook-shaped member, the said spring being attached to the swinging lever and hook-shaped member at points thereof which move in opposite directions to each other, as the top roller moves to and fro on the bottom roller.

6. In a combing-machine of the class wherein a top-detaching roller is moved to and fro on a lower roller relatively to the combing cylinder, the combination with said top roller of an operating lever, a hook-shaped member connecting said operating lever and top roller, a swinging weight lever pivoted to the operating lever, and a tension spring connecting said weight lever and hook-shaped member, said weight lever having a projection to contact with the hook-shaped member, when pressure of the latter on the said top roller is to be relieved.

In testimony whereof I have affixed my signature.

J. W. NASMITH.
